FREE PLAY DEVICE

Joseph H. Tigerman, Chicago, Ill., assignor to
 J. H. Tigerman, Inc., Chicago, Ill., a corpora-
 tion of Illinois

Application June 12, 1936, Serial No. 84,795

8 Claims. (Cl. 273—121)

This invention relates to a free play device.

It is an object of this invention to provide an improved free play device which is relatively simple and inexpensive in construction and efficient in use.

Another object of the present invention is to provide a new free play device for coin-controlled apparatus such, for example, as an amusement apparatus of the so-called pin and marble game type or other coin-controlled apparatus.

An additional object of the present invention is to provide a novel device for controlling the operation of the free play device.

An additional object of the present invention is to provide a novel device for controlling the operation of the free play device in such a manner that the indicator embodied in the same may be moved one or more circumferential steps away from its initial or zero position at each operation thereof, rather than in a constant and predetermined sequence of one circumferential step at each time as in the prior art free play devices.

A further object of the present invention is to provide a novel device for simultaneously operating the resetting mechanism for the free play indicator and the means for moving the ball-retaining member into ball-releasing position, when the free play device is used in conjunction with an amusement apparatus of the so-called pin and marble game type.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a longitudinal vertical sectional view showing a preferred form of the new free play device embodied in an amusement apparatus of the so-called pin and marble game type;

Fig. 2 is a diagrammatic view showing the several electrical circuits embodied in the new device; and

Fig. 3 is a plan view, partly diagrammatic, showing the new free play device, the control mechanism therefor, and the various circuits associated therewith.

A preferred form of the new free play device is shown in the drawings and is therein shown, for the purpose of illustration, as being associated with an amusement apparatus of the so-called pin and marble game type, said amusement apparatus being generally indicated at 10 and comprising a cabinet 11 which includes an inclined

playing board 12; it being understood, however, that while the new free play device is shown as being associated with an amusement apparatus of the so-called pin and marble game type it may be used in conjunction with other coin-controlled apparatus such, for example, as automatic phonographs, and the like.

Provided in the inclined playing board 12 are ball-receiving pockets or exit openings 13 and slidably mounted in the cabinet 11, below the inclined playing board 12, is an operating mechanism in the form of a so-called "shuffle-board" or ball-retaining member 14, and mounted on the ball-retaining member 14 are switches 15 which are adapted to be closed by the action of balls 16 entering the pockets 13.

Provided in the cabinet 11 is an upright wall or support 17 and attached to this wall 17 is a bracket 18 on which is mounted a solenoid 19; this solenoid 19 including a movable element or armature 20 which is attached, as at 21, to the ball-retaining member 14 (Fig. 1). This solenoid 19 is embodied or arranged in an electrical circuit, generally indicated at 22 (Fig. 2) and arranged in this circuit is a control switch in the form of a push button switch 23 which is slidably mounted in the end wall 24 of the cabinet 11 (Fig. 1). Likewise embodied in the circuit 22 is a source of electrical energy which may be a battery of dry cells, or the like, 25 which are shown as being mounted in the cabinet 11 on the bottom wall thereof.

The present invention embodies a new free play device, which is generally indicated at 25, and this free play device includes an indicator or pointer 26 which is fixedly mounted on or attached to a vertically extending rotatable shaft 27 and this indicator 26 is movable over a dial (not shown) but which may be arranged in the cabinet 11 below the transparent or glass top 28 of the same. Likewise mounted on the shaft 27 is a ratchet 29 and engageable with the teeth of the ratchet 29 is a pawl 30 which is pivotally mounted, as at 31, upon a slide bar 32 which is slidably mounted upon a supporting frame 33,

the pawl 30 being normally urged out of engagement with the teeth of the ratchet 29 by a spring 34 (Fig. 3) and the extent of movement of the pawl 30 being limited by a pin and slot connection 35 which it has with the slide bar 32.

The slide bar 32 is attached, as at 36, to the movable element or armature 37 of a solenoid 38 which is mounted upon a supporting frame 39, upon which the frame 33 is likewise mounted, and this solenoid 38 is embodied in an electrical

5

55

circuit 40 which is controlled by a control device or commutator 41, which will be described hereinafter, and which forms the subject matter of my copending application, Serial No. 67,614, filed 5 March 7, 1936, on a coin checking or dispensing device.

Pivotedly mounted, as at 42, upon the supporting frame 33, is an escapement dog 43, and this dog 43 is pivotedly connected, as at 44, to the 10 movable element or armature 45 of a solenoid 46 which is mounted upon the supporting frame 39.

One side of the solenoid 46 is electrically connected, by way of a conductor 47, with one 15 side of the solenoid 46, and the other side of the solenoid 46 is electrically connected, by way of conductors 48 and 49, with the other side of the solenoid 46; while the conductors 48—49 are, in turn, electrically connected, by way of a conductor 50, to a resilient contact 51 of a switch 52 which is mounted on the supporting frame 33. The switch 52 also includes a resilient contact 53 which is somewhat shorter in length than the contact 51 (Fig. 3) so that the contact 51 has 25 an end portion 54 which projects beyond the end of the contact 53. Mounted on the ratchet 29 and projecting upwardly, above the upper surface of the latter, is a lug or pin 55 and this lug 55 is engageable with the end portion 54 of the 30 contact 51 for a reason to be explained hereinafter.

The contact 53 is electrically connected, by way of a conductor 56, with one side of the current source 24, and the other side of the current source 24 is electrically connected, by way of conductors 59 and 57, to one side of the push button or control switch 28; each of the ball-actuated switches 15 including a contact 58 which is electrically connected, by a conductor 59, to the 40 conductor 57.

The control device 41 for the free play device 25 includes an annular row of spaced stationary contacts 60, each of which is electrically connected, by a conductor 63, to the stationary and 45 central contact 64 of the corresponding switch 15, it being noted that central contact 64a of the initial switch 15 (as seen looking left to right in Fig. 3) is electrically connected, by way of the conductor 63a to the initial contact 60a and that 50 the second contact 60b (as seen looking from bottom to top Fig. 3) is electrically connected, by way of conductor 63b to the contact 101a of the switch 15a; and that the middle contact 64b of the second switch 15b is connected, by a conductor 102, to the conductor 63b, for a reason 55 which will be made apparent hereinafter.

The control device or commutator 41 also includes a movable contact 62 which is movable over, and successively into engagement with the 60 stationary contacts 60, this movable contact 62 being fix dly mounted on or attached to a shaft 63 which is rotatably mounted upon a support 64. Likewise mounted on the shaft 63 is a ratchet 65 and engageable with this ratchet 65 is a pawl 66, this pawl 66 being pivotally mounted between its ends, as at 67, upon an upward extension 81 of a rocker arm 75 which is loosely mounted upon, that is, "floats", on the shaft 63; the pawl 66 being urged into engagement with the ratchet 65 by a spring 70. The lower end portion 76 of the rocker arm 75 projects into a slot 77 which is formed in the armature or movable element 82 of a solenoid 78.

75 Likewise loosely mounted on, that is, "floating",

on the shaft 63, is a rocker arm 69 which has an upward extension 83 and this extension 83 is engageable with a stop 88 so as to limit movement of the rocker arm 69 in a clockwise direction (Fig. 3). This rocker arm 69 has a lower 5 end portion 71 and this lower end portion 71 is engageable with a resilient contact 72 of a switch 73 and when disposed in its normal position, as in Fig. 3, the lower end portion 71 of the rocker arm 69 urges the contact 72 into engagement with the contact 74 so as to close the switch 73.

A spring 87 has one end portion attached to the rocker arm 75, as at 85, and has its other end portion attached to the lower end portion 71 of the rocker arm 69, as at 86.

15

Operation

When a ball 16 enters one of the ball-receiving pockets 13 it closes the corresponding switch 15, by bridging the contacts 58 and 64 thereof, whereupon current will flow through the solenoid 78 of the control device 41 as follows: from one side of the current source 24, by way of the conductors 59 and 57, through the corresponding and closed switch 15, through the conductor 63 and corresponding contact 60, through the movable contact 62 (which is at this time disposed in its initial position, that is, in engagement with the initial contact 60a), thence b' way of the ground conductor 91 and conductors 92 and 93 to one side of the solenoid 78, through the latter, and thence by way of the conductors 94 and 95 and switch 73 back to the other side of the current source 24, thereby energizing the solenoid 78; it being understood that the switch 73 is normally closed.

When the solenoid 78 is thus energized it moves its armature 82 (left to right, Fig. 3), and this movement of the armature 82 moves the rocker arm 75 (counterclockwise, Fig. 3) on the shaft 63. During this operation the pawl 66 rides over the ratchet 65 an angular or circumferential distance equal to the angular distance between two of the teeth in the ratchet 65. As the armature 82 of the solenoid 78 is moved (left to right, Fig. 3) it acts, through the lower end portion 76 of the rocker arm 75 and the spring 87, to move the rocker arm 69 (clockwise, Fig. 3) on the shaft 63, thus moving the lower end portion 71 of the rocker arm 69 out of engagement with the resilient contact 72 of the switch 73, whereupon the said contact 72 will move, under the action of its own resiliency, into position to open the switch 73, thereby deenergizing the solenoid 78; the movement of the rocker arm 69 (clockwise, Fig. 3) being limited by the engagement of its upper end portion 83 with the stop 88.

When the solenoid 78 is thus deenergized, by the opening of the switch 73, the tensioned resetting spring 79 returns the armature 82 of the solenoid 78 back to its initial position (as in Fig. 3) and during this operation the armature 77 moves the rocker arm 75 (clockwise, Fig. 3) on the shaft 63, thereby causing the pawl 66 to engage the teeth of the ratchet 65 and move the same, together with the shaft 63 and the movable contact 62 a circumferential distance corresponding to the distance between two of the stationary contacts 60, that is, out of engagement with the initial contact 60a into engagement with the contact 60b, thereby again closing circuit to, and energizing, the solenoid 78, this cycle of operations continuing until the movable contact 62 moves out of engagement with the particular

20

60

65

70

75

contact 60 which corresponds to, and is electrically connected by the corresponding conductor 83, to the particular switch 15 which has been closed by the action of a ball entering one of the 5 pockets 13. Thus, for example, if the ball enters the particular pocket 13 with which the switch 15c is associated the solenoid 78 will be energized, and the control device 41 will be actuated, three successive times, during which operation 10 the movable contact 62 of the commutator or control device 41 will move successively from its initial position, in engagement with the contact 60a, into and out of engagement with the contact 60c whereupon the control device 41 will 15 cease to operate, the movable contact 62 being returned to its initial position by any suitable resetting means (not shown).

It is to be noted that when the parts are in their initial position, the lug 55 on the ratchet 20 29 is disposed in engagement with the end portion 54 of the contact 51, thereby maintaining the switch 52 in open position. However, when the solenoid 78 is energized, as above set forth, to operate the control device 41, circuit is also closed 25 to the solenoid 38 so as to operate the free play device 25, current then flowing as follows: from one side of the current source 24, by way of the conductors 89 and 96 to one side of the solenoid 38, through the latter, and then by way of the 30 conductors 97 and 95 and switch 73 back to the other side current source 24, thereby energizing the solenoid 38.

When the solenoid 38 is thus energized it will attract its movable element or armature 37 and 35 the slide bar 32 (downwardly, as seen in Fig. 3) against the action of the resetting spring 98, thereby moving the pawl 30 into engagement with the teeth of the ratchet 29. Accordingly, when the switch 13 is opened, in the manner hereinbefore set forth, the tensioned resetting spring 98 will move the slide bar 32 and armature 37 back into their initial positions (as seen in Fig. 3), and during this operation the pawl 30 will engage the teeth of the ratchet 29 and move the 40 latter, shaft 27, and indicator 26 one circumferential step (counterclockwise, Fig. 3), and the indicator 26 will then show that the player has one free play to his credit.

When the player has one or more free games 50 to his credit, as shown by the indicator 26, that is, when the indicator 26 is away from its initial or zero position, the player may move the ball-retaining member or so-called "shuffle-board" 55 12 into ball-releasing position by operating the control switch 23, which may be of the push button type, or any other desired type, whereupon, when the control switch 23 is closed the operating solenoid 19 for the ball-retaining member 14 will be energized, current then flowing as follows: 60 from one side of the current source 24, by way of the conductor 56, switch 52, and conductors 50 and 49, into one side of the solenoid 19, through the latter, and then by way of the conductor 98, switch 23 and conductors 57 and 89 back to the 65 other side of the current source 24, thereby energizing the operating solenoid 19 for the ball-retaining member 14.

When the operating solenoid 19 for the ball-retaining member 14 is thus energized it will 70 act upon its movable element or armature 20 to move the latter (right to left, Fig. 1), thereby moving the slideable ball-retaining member 14 (right to left, Fig. 1) into ball-releasing position, that is, into position to release the balls 16 from

the pockets 13 in the inclined playing board 12; the ball-retaining member 14 being returned to its initial position by a conventional resetting spring (not shown). In this manner the player is enabled to play a free game upon the amusement apparatus 10, with which the present invention is associated, in the embodiment of the invention shown in the drawings, without inserting a coin into or operating the coin slide 99 which, as is well understood in the art, has a 10 conventional operative connection (not shown) with the ball-retaining member 14 for operating the latter.

The control device 41 includes a lever 106 (Fig. 3) which is pivotally mounted between its 15 ends in the cabinet 11, as at 107, and this member 106 has an upper end portion 104 which is engageable with an arm or bracket 105 which is attached to and depends from the slideable ball-retaining member 14 (Fig. 1). The upper end 20 portion 104 of the lever 106 is engageable with an upwardly extending arm 109 of the pawl 66.

Accordingly, each time the ball-retaining member 14 is moved (right to left, Fig. 1) into ball-releasing position, the depending arm 105 thereof 25 will engage the upper end portion 104 of the lever 106 and will pivot the latter, at 107, (counterclockwise, Fig. 3), thereby moving the upper end portion 104 of the lever 106 into engagement with the upwardly extending arm 109 of the pawl 30 66 and thus moving the pawl 66 out of engagement with the ratchet 65, whereupon the tensioned resetting coil spring 108 for the ratchet 65 will move the latter and the shaft 63 and the movable contact 62 of the control device 41 one 35 circumferential step (counterclockwise, Fig. 3), that is, a circumferential distance equal to the circumferential distance between two of the stationary contacts 60 of the commutator 41. This operation is repeated each time the circuit to 40 the solenoid 19 is closed, by the switch 23, to operate the ball-retaining member 14, so that when the latter has been operated a number of times equal to the number of free plays the player has to his credit, as indicated by the free play 45 indicator 26, the movable contact will be back in its initial position, that is, in engagement with the contact 60a. It is to be noted, in this connection, that the lever 106 is returned to its initial position, (as, in Fig. 3) after each operation there- 50 of, by its resetting spring 110.

When the operating solenoid 19 for the ball-retaining member 14 is energized, the operating solenoid 46 which operates the resetting device 43 for the free play indicator 26 is likewise energized, current then flowing as follows: from one side of the current source 24, by way of the conductor 56, through the switch 52, through the conductors 50 and 48 into one side of the solenoid 46, through the latter, and then by way of the conductors 47 and 98, switch 23, and conductors 57 and 89 back to the other side of the current source 24.

When the operating solenoid 46 for the resetting device (for the free play device 41) is thus energized it will attract its movable element or armature 45, against the action of its resetting spring 100, (downwardly as seen in Fig. 3) thereby pivoting the pawl 43, at 42, (counterclockwise, Fig. 3). This movement of the pawl 43 moves the arm 102 thereof out of engagement with the teeth of the ratchet 29 and at the same time moves the arm 101 of the pawl 43 into engagement with the teeth of the ratchet 29, thus moving the ratchet 29 and the free play indicator 70 75

26 one circumferential or angular step back toward their initial positions, (clockwise, Fig. 3), this resetting operation being repeated each time the control switch 23 is operated to play a free 5 game upon the amusement apparatus 10 with which the present invention is associated.

Accordingly, when the free play indicator 26 and the ratchet 29 are reset back into their initial positions, the lug or pin 55 on the ratchet 29 will 10 engage the end portion 54 of the contact 51 and will thereby move the latter out of engagement with the contact 53, thus opening the switch 52 and breaking circuit both to the operating solenoid 19 for the ball-retaining member 14 and to 15 the operating solenoid 46 for the resetting mechanism 43 of the free play device 25, it being noted that the contacts 51 and 53 of the switch 52 are normally urged into engagement with each other by their own resiliency. It is to be noted, how- 20 ever, that when the free play device 25 is in its normal or initial position, the pin or lug 55 on the ratchet 29 is disposed in engagement with the end portion 54 of the contact 51, thus main- 25 taining the switch 52 in open position, and that when the switch 52 is opened circuit can not be closed to either of the solenoids 46 and 19, by operating the manual control switch 23, and hence the player can not move the ball-retaining member 14 into ball-releasing position by oper- 30 ating the manual control switch 23 when the free play device 25 is in its normal or initial position.

It is also to be noted that in the present free play device the player may become entitled to one or more free plays when a ball 16 enters one 35 of the pockets 12, rather than being limited to but one free play for each ball, as in the prior art free play devices.

It will be noted, (Fig. 3) that the stationary contacts 60f to 60j, inclusive, are tied together 40 into one unit by means of a conductive strip 163 so that if a ball 16 enters into the particular pocket 13 which has the switch 15f associated therewith the movable contact 62 of the control device or commutator 41 will move from its initial 45 position in engagement with the contact 60a successively into engagement with the stationary contacts 60a, 60b, 60c, 60d, 60e, 60f, 60g, 60h, 60i, and 60j, thus closing circuit ten (10) times 50 in succession to the solenoids 18 and 38 and thus moving the free play indicator 26 ten circumferential steps (counterclockwise, Fig. 3), thereby indicating that the player is, and thus entitling him to, ten free plays.

While I have illustrated and described the preferred form of construction for carrying my invention into effect, this is capable of variation and modification, without departing from the spirit of the invention. I, therefore, do not wish to be limited to the precise details of construction set 60 forth, but desire to avail myself of such variations and modifications as come within the scope of the appended claims.

Having thus described my invention, what I claim as new and desire to protect by Letters 65 Patent is:

1. A free play device for an amusement apparatus of the type which includes a cabinet having an inclined playing board provided with ball-receiving pockets, and a ball-retaining member 70 slidably mounted in the said cabinet below the said inclined playing board for temporarily retaining therein balls which enter into said pockets, said free play device comprising a free play indicator movably mounted in or adjacent to the said 75 cabinet, control means actuated by a ball entering

one of the said pockets for moving said indicator in a direction away from its initial or zero position at each operation thereof, said control means including a device for moving the said indicator alternatively one or a plurality of steps at each operation thereof, the number of said steps at each operation being determined by the particular one of the said pockets the said ball enters. 5

2. A free play device for an amusement apparatus of the type which includes a cabinet having an inclined playing board provided with ball-receiving pockets, and a ball-retaining member 10 slidably mounted in the said cabinet below the said inclined playing board for temporarily retaining therein balls which enter into said pockets, 15 said free play device comprising a free play indicator movably mounted in or adjacent to the said cabinet, control means actuated by a ball entering one of the said pockets for moving the said indicator in a direction away from its initial or zero position at each operation thereof, said control means including a device for moving the said indicator alternatively one or a plurality of steps in a direction away from its initial or zero position at each operation thereof, the number of said steps 20 at each operation being determined by the particular one of the said pockets the said ball enters, means for resetting the said free play indicator back into its initial position, means for moving the said ball-retaining member into ball-releasing position, and means for simultaneously operating both the said resetting means for the said free play indicator and the said means for moving the said ball-retaining member into ball-releasing 25 position. 30

3. A free play device for an amusement apparatus of the type which includes a cabinet having an inclined playing board provided with ball-receiving pockets, and a ball-retaining member 40 slidably mounted in the said cabinet below the said inclined playing board for temporarily retaining therein balls which enter into the said pockets, said free play device comprising a free play indicator movably mounted in the said cabinet, control means actuated by a ball entering one 45 of the said pockets for moving the said indicator in a direction away from its initial or zero position at each operation thereof, said control means including a device for moving the said free play indicator alternatively one or a plurality of steps in a direction away from its initial or zero position at each operation thereof, the number of said steps 50 at each operation being determined by the particular pocket the said ball enters, means for resetting the said free play indicator back into its initial position, means for moving the said ball-retaining member into ball-releasing position, means for simultaneously operating both the said resetting means for the said free play indicator and the said means for moving the said ball-retaining member, and means for preventing operation of the said means for moving the said ball-retaining member, and of the said 55 resetting means for the said free play indicator, when the said free play indicator is in its initial or zero position. 60

4. A free play device for an amusement apparatus of the type which includes a cabinet having an inclined playing board provided with ball-receiving pockets, and a ball-retaining member 70 slidably mounted in the said cabinet below the said inclined playing board for temporarily retaining therein balls which enter into the said pockets, said free play device comprising a free play indicator 75

movably mounted in or adjacent to the said cabinet, control means actuated by a ball entering one of the said pockets for moving the said free play indicator in a direction away from its initial or zero position at each operation thereof, said control means including a device for moving the said free play indicator alternatively one or a plurality of steps in a direction away from its initial or zero position at each operation thereof, the 5 number of said steps at each operation being determined by the particular one of the said pockets the said ball enters, means for resetting the said free play indicator back into its initial position, means for moving the said ball-retaining 10 member into ball-releasing position, and a manual control member movably mounted in a wall of the said cabinet for simultaneously operating both the said resetting means for the said free play indicator and the said means for moving the said 15 ball-retaining member into ball-releasing position.

5. A free play device for an amusement apparatus of the type which includes a cabinet having an inclined playing board down which playing balls are adapted to travel, said free play 20 device comprising a free play indicator movably mounted in or adjacent to the said cabinet, and control means actuated by a ball traveling down the said inclined playing board for moving the said free play indicator in a direction away from its initial or zero position at each operation thereof, said control means including a device for moving the said free play indicator alternatively one or a plurality of steps away from its initial or zero position at each operation thereof.

25 6. A free play device for an amusement apparatus of the type which includes a cabinet having an inclined playing board down which playing balls are adapted to travel, said free play device

comprising a free play indicator movably mounted in or adjacent to the said cabinet, control means actuated by a ball traveling down the said inclined playing board for moving the said free play indicator in a direction away from its initial or zero position at each operation thereof, said control means including a device for moving the said free play indicator alternatively one or a plurality of steps in a direction away from its initial or zero position at each operation thereof, and 10 means for resetting the said free play indicator back into its initial position.

7. A free play device for an amusement apparatus of the type which includes a cabinet or casing having a surface over which a ball may be 15 played, said free play device comprising a free play indicator movably mounted in or adjacent to the said cabinet, and control means actuated by a ball in the said cabinet for moving the said free play indicator in a direction away from its 20 initial or zero position, said control means including a device for moving the said free play indicator a variable number of steps away from its initial or zero position at each operation thereof.

25 8. A free play device for an amusement apparatus of the type which includes a cabinet or casing having a surface over which a ball may be played, said free play device comprising a free play indicator movably mounted in or adjacent to the said cabinet, and control means actuated by a ball in the said cabinet for moving the said free play indicator in a direction away from its initial or zero position, said control means including a device for moving the said free play indicator 30 a plurality of steps away from its initial or zero position at each operation thereof.

JOSEPH H. TIGERMAN.
